US00D779888S

(12) **United States Design Patent** (10) **Patent No.:** **US D779,888 S**
(45) **Date of Patent:** **** Feb. 28, 2017**

(54) **CANDY DISPENSER**

(71) Applicant: **JOBAR INTERNATIONAL, INC.**,
Carson, CA (US)

(72) Inventor: **Tim Alan Baker**, Torrance, CA (US)

(73) Assignee: **Jobar International, Inc.**, Carson, CA
(US)

(**) Term: **14 Years**

(21) Appl. No.: **29/461,772**

(22) Filed: **Jul. 26, 2013**

(51) LOC (10) Cl. **07-06**

(52) U.S. Cl.

USPC **D7/589**

(57) **CLAIM**

The ornamental design for a candy dispenser, as shown and described.

DESCRIPTION

FIG. 1 is a perspective view of a candy dispenser showing my new design;

FIG. 2 is a front view thereof;

FIG. 3 is a right side view thereof, and is the same as the left side view;

(Continued)

FIG. 4 is a back side view thereof;
 FIG. 5 is a top view thereof; and,
 FIG. 6 is a bottom view thereof.
 The broken lines shown in FIGS. 1-6 represent portions of
 the candy dispenser that form no part of the claimed design.

1 Claim, 6 Drawing Sheets
